ATTORNEY.

UNITED STATES PATENT OFFICE.

DOMINICK KULAGE, OF ST. LOUIS, MISSOURI.

WEATHER-STRIP UNIT.

Application filed August 3, 1925. Serial No. 47,692.

This invention relates to improvements in weatherstripping, and has for its object the provision of a weatherstrip piece or unit adapted to be inserted on the parting strips 5 of a window sash between the meeting rails of the upper and lower window frames.

As is well known, in ordinary window construction, the meeting rails of the frames of the upper and lower windows are recessed in 10 their outer edge portions to receive the parting strips located between the two frames, so that the opposed faces of the meeting rails may be in contact beyond the outer face of the parting strips. This construction results in leaving a considerable space between 15 the bottoms of these recesses and the faces of the parting strips through which cold air may enter.

Heretofore, attempts have been made to 20 close these spaces by securing to the face of the parting strip, as by glue, tacks, or the like, a short strip of felt of substantially the width of the parting strip and of a length corresponding to the height of the meeting 25 rails. The objection to such procedure is that in severely cold weather, the felt piece will frequently freeze to the window frame and be torn from the parting strip when the window is raised. The same result frequently follows after a rain, when the felt 30 will be caused to adhere to the frame and be torn away in lifting the window.

According to my invention, I employ a suitable strip of filling material, such as felt, 35 and secure the same on the inner face of a strip of metal of substantially the width, but slightly longer than, the piece of felt, and having its ends bent inward and apertured so that the device may be readily secured by 40 tacks to the outer face of the parting strip. In this application, the felt is placed next to the parting strip, leaving the metal to form the contact with the bottoms of the recesses in the meeting rails, thus presenting a 45 smooth surface for the rails to slide over, and preventing the felt strip from coming in contact with said rails. This, of course, avoids any possibility of the felt filling strip adhering or being frozen to the meeting rails, 50 or, in fact, of coming in contact therewith at all.

In the accompanying drawing, illustrating my invention:—

Figure 1 is a horizontal sectional view 55 through a portion of one side of a window

sash and the adjacent portions of the meeting rails of two window frames, the view being taken along the line of the upper surface of the meeting rail of the inside or lower window;

Figure 2 is a section on the line 2—2 of Figure 1; and

Figure 3 is a perspective view of my weatherstrip unit.

Referring now to the drawing, the numeral 1 indicates one of the side members of a window sash, 2, the parting strip thereof, 3, the meeting rail of the lower window frame, and 4, the meeting rail of the upper window frame. In order to permit these 65 rails to engage beyond the parting strip 2, the meeting rail 3 is provided with an L-shaped recess 5, and the meeting rail 4 with a similar, but shallower, recess 6, these recesses receiving the parting strip 2, as shown 70 by Figure 1, and permitting the opposed faces of the meeting rails to engage, as indicated along the line 7. This construction leaves a space 8 between the bottom of the recesses in the meeting rails and the outer 75 face of the parting strip at each side of the window, which space invariably increases to a considerable extent, owing to the shrinkage of the wood of the meeting rails and parting strip, especially under modern conditions which obtain throughout the lumber and milling industry, where no effort is made to adequately dry the lumber used in construction work. These spaces permit quite an 80 amount of cold air to enter the room, thus 85 increasing the difficulty and expense of heating.

According to my invention, I fill up this space by the use of a weatherstrip unit constructed as shown in Figures 2 and 3.

Referring to these figures, the numeral 9 indicates a strip of any suitable filling material, preferably felt, which is secured on the underside of a strip of metal 10, the preferred securing means being a staple 11 passed through apertures in the strip 10 and through the felt, and its ends being clinched, or turned inward, on the inner side of the felt strip, as indicated by dotted lines at 12 in Figure 2. In this operation, the head or 100 body of the staple is caused to indent or bend inward the body of the metal strip, so that the outer surface of said head lies substantially flush with the outer face of the metal strip, as shown by Figure 3. The head or 105

body of this staple is moreover disposed longitudinally of the metal strip in order to offer no obstruction to the movement of the window frame in engagement therewith.

5 The ends of the metal strip extend beyond the ends of the felt strip and are bent inward, as indicated at 13, so as to present a flat portion 14 to engage the face of the parting strip. This flat portion is provided with

10 apertures 15 through which tacks 16 may be driven to secure the unit to the parting strip.

2. Preferably, the outer edge portion of the metal strip 10 throughout its length is bent inward slightly, as indicated at 17, to

15 strengthen the structure.

I may use any suitable non-corrosive metal for the strip 10, but prefer either copper, bronze or zinc.

Various changes may be made in the details of construction and in the shape, material and arrangement of the parts as the same are herein shown and described, without departing from the broad idea of my invention.

25 I claim:

1. A weather-strip unit comprising a strip of metal having a shorter strip of felt, or the like, secured thereon, said metal strip having its ends bent inward and apertured.

20 2. A weatherstrip unit comprising a strip of metal having a shorter strip of felt, or the like, secured thereon, said metal strip having its edge portion bent downwardly to strengthen the structure.

3. A weatherstrip unit comprising a strip of metal, a shorter strip of felt, or the like, applied to one side of said metal strip, and a staple passed through said strips to secure them together.

40 4. A weatherstrip unit comprising a strip of metal, a shorter strip of felt, or the like, applied to one side of said metal strip, and a staple passed through said strips to secure them together and disposed longitudinally of the unit.

45 5. A weather strip unit comprising a strip of metal, a shorter strip of felt, or the like, applied to one side of said metal strip, and a staple passed through said strips to secure them together and disposed longitudinally of the unit, the head of said staple lying against the outer face of the metal strip and disposed longitudinally thereof, and the legs of the staple being clinched against the strip of felt.

50 6. A filler weatherstrip comprising a front member and a body member of compressible material secured thereto, said front member having a substantially flat contacting portion and attaching portions extending beyond said body member and positioned in a plane substantially parallel to the plane of said contacting portion and removed there-

from a distance substantially equal to the thickness of said body member.

65 7. A filler weatherstrip comprising a front member and a body member secured thereto of compressible material of less length than said front member, said front member having a substantially flat contacting portion substantially the same length as said body member and having the ends thereof inclined inwardly at the ends of said body member, said ends being shaped and arranged to form attaching portions positioned in a plane substantially parallel to the plane of said contacting portion and removed therefrom a distance substantially equal to the thickness of said body member.

8. A filler weatherstrip applied between the parting bead of a window and the bottom and sides of a notch cut in the meeting rails of the window sash and comprising a front member and a body member of compressible material secured thereto, said weatherstrip being constructed and arranged whereby the contacting portion of said front member will be substantially the length of said body member and will be substantially parallel to the bottom of said notch.

9. A filler weatherstrip applied between the parting bead of a window and the bottom of a notch cut in the meeting rails of the window sash and comprising a front member and a body member of compressible material of less length than said front member and secured thereto, said front member having a contacting portion substantially the same length as said body member and substantially parallel to the bottom of said notch and having the ends thereof inclined inwardly at the ends of said body member, said ends being shaped and arranged to form attaching portions positioned in a plane substantially parallel to the plane of said contacting portion and removed therefrom a distance substantially equal to the thickness of said body member.

10. A filler weatherstrip applied between the parting bead of a window and the bottom and sides of a notch cut in the meeting rails of a window sash and comprising a front member and a body member of compressible material secured thereto, said body member being of greater width than said parting bead and having a part thereof projecting outwardly at each side of said parting bead, said weatherstrip being positioned and arranged so that said front member will contact with the bottom of said notch and the projecting parts of said body member will contact with the sides of said notch.

In testimony whereof, I have hereunto set my hand.

DOMINICK KULAGE.
